UNITED STATES PATENT OFFICE.

HARRY W. JONES, OF INDEPENDENCE, KANSAS; FRANK E. JONES, ADMINISTRATOR OF SAID HARRY W. JONES, DECEASED, ASSIGNR TO THE KANSAS CITY GASOLINE COMPANY, OF KANSAS CITY, KANSAS, A CORPORATION OF KANSAS.

APPARATUS FOR CRACKING PETROLEUM.

1,347,543.

Specification of Letters Patent.

Patented July 27, 1920.

Original application filed May 27, 1916, Serial No. 100,278. Divided and this application filed February 13, 1918. Serial No. 216,937.

To all whom it may concern:

Be it known that I, HARRY W. JONES, a citizen of the United States, residing at Independence, in the county of Montgomery and State of Kansas, have invented certain new and useful Improvements in Apparatus for Cracking Petroleum, of which the following is a specification, reference being had therein to the accompanying drawing.

10 My invention relates to the art of refining liquid hydrocarbons, and has for its object the production of improved apparatus particularly adapted for cracking petroleum oils and vapors, with safety, efficiency and 15 economy. The present is a division of my copending application Serial No. 100,278, filed May 27, 1916.

In order to attain my object, I resort to subdivision of the apparatus, or rather a 20 multiplication of units to form a battery or batteries, of which the principal elements are all connected in parallel, with suitable cut-offs and pressure valves so arranged that individual units or elements may be cut in 25 and cut out with facility. Some of the individual elements may for special reasons be included in series or in tandem with others, but the general principle of the present invention is to connect up the batteries in 30 parallel, for reasons which will hereinafter fully appear.

My invention is shown in the diagrammatic drawing herewith, in which 80—84 are a series of oil tanks; 85—89 are supply pipes 35 therefrom; 91—95 control valves; 90 is a manifold receiving and blending the oils from the tanks or sources; 110 to 116 are compressors arranged in a battery, or in parallel, to handle quantities in small units, subdivided in compression, united and redistributed for cracking, through the pressure manifold 138; 145 to 149 are small cracking coils, in separate furnaces; 140—144 and 156—160 40 their intake pipes and valves; 150—154 and 45 161—165 their discharge pipes and valves; 155 the collecting manifold; 756 a relief air chamber to deaden compression shocks; 166—168 discharge pipes to condensers 172— 50 174, and 169—171 valves therefor. From the condensers the usual discharge pipes are taken through valves to receiving tanks.

The tanks 80, 81, 82, 83, 84 are storage and supply tanks of usual type, from which

the oil is usually fed by gravity as determined by manipulating valves 91, 92, 93, 55 94 and 95, respectively. The manifold 90 is of sufficient capacity to maintain a full supply without pressure for the battery of compressors 110, 111, 112, 113, 114, 115, and 116. The valves 103 to 109 inclusive 60 being individual to the compressors are used only in connection therewith. Each compressor is preferably a multiple stage high pressure pump of standard commercial type, which need not be specifically described 65 herein, as its structure forms no part of the present invention. The valves 124 to 130 inclusive are for the purpose of taking any back pressure off the compressor valves when any particular unit compressor is stopped 70 or cut out.

The manifold 138 receives its compression from all the compressors in service at a given time and is constructed of steel to resist the maximum pressure due to the entire 75 battery. Relief chambers 131 to 137 and 139, shown in diagram only and supposed to contain air or gas, renewed when necessary as well understood in the art, are for cushioning back pressures and to smooth 80 the peaks of curves of variation in either pump or autogenous compression.

The separate cracking coils 145 to 149 inclusive, and their furnaces, are of the general type heretofore described by me in my 85 parent application of which this is a division and in such patents as those to Albert R. Jones, No. 1,328,522 and to Frank E. Wellman, No. 1,328,468, both granted January 20, 1920, but it is to be understood that my 90 invention is not limited to these, as coils or cracking retorts of any commercially equivalent form are contemplated.

The valves 161 to 165 inclusive are pressure retaining valves, as are also the valves 95 169 to 170, and the valves beyond the condensers 172 to 174, so that the pressures in the cracking stills or retorts may be distributed and regulated at will. A relief chamber 756 is also shown, of the same general type as 139.

By this arrangement, the cracking is done in small units, with much greater tensile resistance of their walls to pressure strains; and the compression is done by small units 105 in a battery with similar resisting powers;

in addition to which the entire system is flexible, not subject to shut down by the explosion or disabling of one unit, and yet giving an approximately uniform distribution of liquids and pressure.

What I claim and desire to secure by Letters Patent of the United States is:

A system for cracking petroleum oils, comprising a set of tanks in parallel, a manifold pipe therefor, a battery of compressors in small units, a suction pipe from said manifold to each compressor with a valve therein, a pressure manifold common to said compressors, a discharge pipe from each com-

pressor to said manifold, a valve in each of 15 said pipes, a subdivided set or battery of small cracking still units set in separate furnaces and all fed from said pressure manifold, with separate valved connections thereto, a collecting manifold and separate valved 20 discharge connections from the individual stills thereto and a condensing system connecting to said collecting manifold, and adapted to deliver the condensed products to the usual receiving devices. 25

In testimony whereof I affix my signature.

HARRY W. JONES.
